UNITED STATES PATENT OFFICE.

GUY OTIS BREWSTER, OF NEW YORK, N. Y.

DESIGN FOR A JAR OR SIMILAR ARTICLE.

Application filed September 11, 1922. Serial No. 3,674. Term of patent 3½ years.

To all whom it may concern:

Be it known that I, GUY OTIS BREWSTER, a citizen of the United States, and a resident of the city, county, and State of New York, have invented a certain new, original, and ornamental Design for a Jar or Similar Article, of which the following is a specification, reference being had to the accompanying drawing, forming part thereof.

In the drawing,
Figure 3 is an end view.

I claim:

The ornamental design for a jar or similar article, as shown.

GUY OTIS BREWSTER.
